Inventor:

George Feuerholz

UNITED STATES PATENT OFFICE.

GEORGE FEUERHOLZ, OF ST. LOUIS, MISSOURI.

SOLE-ATTACHING MEANS.

1,322,555.

Specification of Letters Patent. Patented Nov. 25, 1919.

Application filed January 27, 1919. Serial No. 273,427.

To all whom it may concern:

Be it known that I, GEORGE FEUERHOLZ, a citizen of the United States, and resident of St. Louis, Missouri, have invented certain new and useful Improvements in Sole-Attaching Means, of which the following is a specification.

This invention relates to improvements in sole attaching means and has for its object to provide an insole suitably slit to form tongues against which is stitched or otherwise rigidly secured the lining, the upper, and the welt together with the outer or tread sole so as to form a substantially leak-proof shoe.

The most essential feature of my invention is to provide a system of slitting the insole forming integral tongues to which the lining and upper is sewed in such a manner that the stitches are absolutely covered and concealed from contact either from within or without, thus the foot of the wearer has a perfectly smooth foot surface.

Figure 1 is a sectional view showing the manner of slitting the insole.

Fig. 2 is a sectional view showing the slits partially spread forming the tongues.

Fig. 3 is a sectional view showing the tongues, and the lining inserted in position.

Fig. 4 is a sectional view showing the position of the lining and shoe upper in position with the tongues.

Fig. 5 is a sectional view showing all of the parts ready to be connected together in order to assemble my improved leakproof shoe.

Fig. 6 is a detail sectional perspective view of a portion of the welt strip.

Fig. 7 is a perspective view of the welt strip made use of in connection with my invention.

Fig. 8 is an enlarged detail cross sectional view of a shoe embodying my invention, showing same complete.

Fig. 9 is a detail sectional perspective view of a portion of the insole, showing the reverse side.

Fig. 10 is a side view of a complete shoe embodying my invention.

In the general construction of my invention I provide an insole 11 of a required thickness, and which when slit as will be hereinafter described constitutes the essential feature of my invention.

The underside of the insole 11 is slit as indicated by the numeral 12 forming a tongue

or flap 13 and a channel 14 which will accommodate one end of the stitches 15 by which the lining 16 and shoe upper 17 are held fast to the insole. 60

The edge of the insole is twice slit as indicated by the numerals 18 and 19 forming tongues 20, 21, and 22 the uses of which will be fully hereinafter described.

These tongues 20, 21, and 22 are suitably spread apart forming recesses 23 and 24. In the recess 23 is inserted the shoe lining 16 and the upper 17 assuming a position as shown in Figs. 4 and 8. 65

The upper 17 is permitted to project sufficiently forming an extension 25 and of a length to accommodate the extension or tongue 22 of the insole.

Against the upper and on top of the extension 25 is placed a welt strip 26 which is 70 in the approximate shape of a horse shoe as illustrated in Fig. 7, and it has a downwardly bent edge 27 which contacts with the upper 17.

The welt when placed in position as shown 80 in Fig. 8, binds the lining and upper in position and is firmly held by the stitches 15 which is passed through the extension of the welt, upper, lining and portion of the insole and extends to the channel 14 formed 85 by the slit 12.

This stitching is completely concealed and cannot come in contact either with the foot of the wearer or the surface with which the shoe is brought in contact. 90

When these several parts have been assembled together, the outer sole 28 is attached, this is done by placing the sole against the bottom of the insole 11 and securing the same by stitches 29, see Fig. 8, 95 which stitches pass through the outer sole, extension of the insole, extension of the upper and the welt.

A shoe when so assembled makes a substantially water proof joint, preventing 100 water from in any way seeping into the shoe. It also provides a smooth contact surface for the foot upon the insole, as no stitches project through onto the surface.

I claim—

A shoe comprising an insole, the edge of said insole being provided with two slits so as to form integral projecting tongues, a channel formed in the bottom of said insole, a short distance from the outer edge thereof, the upper and lining inserted in the upper slit and suitably bent to contact and lie 110

on top, the bottom tongue of the lower slit, a welt strip laid on top of the upper, a horizontal stitch passing through the welt, upper and insole and concealed in the channel on the bottom of said insole, an outer sole, and vertical stitches passing through the welt, upper, insole and outer sole.

In testimony whereof I have signed my name to this specification, in presence of two subscribing witnesses.

GEORGE FEUERHOLZ.
